SPRING RELEASE MECHANISM

Frank E. Harrison, Seattle, Wash.

Application December 10, 1945, Serial No. 634,133

3 Claims. (Cl. 29—227)

(Granted under the act of March 3, 1883, as
amended April 30, 1928; 370 O. G. 757)

1

This invention relates to spring release mechanisms and more particularly to mechanisms for releasing compression springs from compressed condition.

In repairing, dismantling or otherwise performing operations on certain types of equipment, it is frequently necessary to release compressed springs that yield considerable force on their release. An example of such equipment is 20 mm. antiaircraft guns, in which relatively large size helical compression springs are employed as equalizer springs and are retained in compressed state by stay bolts. In the absence of specially designed release mechanisms, releasing of such springs may be both hazardous and time consuming.

Objects of the present invention are to provide improved mechanisms for releasing compressed springs safely and expeditiously; to provide mechanisms for safely absorbing the force or energy yielded on release of compression springs; to provide release mechanisms that are adjustable as to size of springs accommodated; and to provide for carrying out the foregoing objects in a facile, economical and efficient manner.

In accomplishing these and other objects of the present invention, I have provided improved details of structure, the preferred form of which is illustrated in the accompanying drawing, wherein the figure is a side elevational view, partly in section, of a spring release mechanism embodying the features of the present invention.

Referring more in detail to the drawing:

The mechanism of my invention comprises a tubular barrel 1 of considerable length, preferably supported in a substantially horizontal position. The support means for the barrel may conveniently include legs formed of pipe sections joined to form a pair of tripods 2 and 3, one of which is secured to the barrel adjacent each end thereof.

The walls of the barrel have one or more pairs of diametrically opposed transverse apertures 4 and 5, proximate to the end of the barrel disposed toward the right as viewed in the figure. The transverse apertures are spaced from said end by distances equivalent to the compressed lengths of the different types of springs with which it is intended to use the device. The barrel is preferably many times longer than the springs even when the latter are released.

Guide means, including a plate 6 having a tubular socket member 7 fixed thereto, are supported on the barrel for longitudinal adjustment by a pair of arcuate clamp members 8. The sock-

2

et in the member 7 is adapted to be aligned with any of pairs of transverse openings 4 or 5.

A retaining pin 9 is slidably carried in the socket member 7, and is adapted to protrude into the inside of the barrel through the aperture 4 or 5 with which the socket is aligned. A lever or handle 10 is pivoted to the upper portion of the plate 6 and carries an arm 11 fixed thereto. Preferably a brace 12 is fixed to the arm and handle to strengthen the structure. A link 13 is pivotally connected to the free end of the arm 11 and to the upper end of the pin 9.

A thrust collar 14 is threadedly engaged with the end of the barrel proximate to the transverse apertures 4 and 5. The collar 14 preferably has an annular insert 15 secured therein and is equipped with handles 16 to facilitate rotation thereof.

The opposite end of the barrel carries abutment means 17 which may conveniently comprise a sleeve secured within the barrel by a bolt in such manner as to leave clearance at the sides thereof.

25

Operation

The plate 6 is adjusted longitudinally of the barrel 1 until the socket 7 is aligned with the transverse apertures 4 and 5 spaced from the collar 15 by a distance equivalent to the compressed length of the spring to be released. The handle 10 is rotated in a counter-clockwise direction as viewed in the figure to project the pin 9 through the transverse apertures into the barrel. The collar 14 is removed and a compressed spring to be released is inserted into the barrel behind the retaining pin and the collar is replaced.

The nut on the stay bolt of the spring is removed by use of a suitable tool, not shown, inserted through the opening in the annular insert 15. In this condition the spring is held compressed by engagement with the retaining pin 9 and with the thrust collar 16.

The lever or handle 10 is rotated in a clockwise direction, as viewed in the figure, thus withdrawing the retaining pin 9 from the barrel. Such withdrawal releases the spring and stay bolt, which are driven through the length of the barrel by the force of the spring yielded on release. Motion of the spring and stay bolt is arrested by engagement of the elements with the abutment means 17. Thus the entire force or energy of the spring yielded on release thereof is expended within the barrel, which safely absorbs the energy.

55 It is possible to release a number of springs

before it becomes necessary to eject the springs and bolts from the barrel. The ejection is easily accomplished by inserting a slender tool (not shown) into the barrel at either side of the abutment means 17, thus pushing the springs out of the barrel, the thrust collar having been removed and the retaining pin retracted.

While I have shown but one embodiment of my invention, it is susceptible to modification without departing from the spirit of the invention. I do not wish, therefore, to be limited by the disclosures set forth, but only by the scope of the appended claims.

The invention described herein may be manufactured and used by or for the Government of the United States of America for governmental purposes without the payment of any royalties thereon or therefor.

I claim:

1. A spring release mechanism comprising an elongated tubular barrel having a plurality of transverse apertures spaced from an end by a distance equivalent to the compressed length of springs to be released, guide means supported on said barrel for longitudinal adjustment and having a socket adapted to be aligned with any one of said transverse apertures, a retaining pin slidably mounted in said socket and adapted to project into said barrel through the transverse aperture aligned with said socket, a lever pivoted to said guide means, linkage means operatively connecting said retaining pin and said lever, a thrust collar removably secured to the end of said barrel proximate to said transverse apertures and having an access aperture therethrough, and abutment means carried by said barrel adjacent the opposite end thereof.

2. A spring release mechanism comprising an elongated tubular barrel having at least one transverse aperture spaced from an end by a distance equivalent to the compressed length of spring to be released, guide means supported on

said barrel and having a socket aligned with said transverse aperture, a retaining pin slidably mounted in said socket and adapted to project into said barrel through said transverse aperture, a lever pivoted to said guide means, linkage means operatively connecting said retaining pin and said lever, a thrust collar removably secured to the end of said barrel proximate to said transverse aperture and having an access aperture therethrough, and abutment means carried by said barrel adjacent the opposite end thereof.

3. A spring release mechanism comprising an elongated tubular barrel having at least one transverse aperture, guide means supported on said barrel, a retaining pin slidably supported in said guide means and adapted to project into said barrel through said transverse aperture, means mounted on said guide means for projecting and retracting said retaining pin through said aperture, a thrust collar removably secured to an end of said barrel and having an access aperture therethrough, and abutment means carried by said barrel adjacent the opposite end thereof.

FRANK E. HARRISON.
